ROD ANTENNA FOR SHORT WAVES

Willi Voigt, Berlin, Germany, assignor to Telefunkens Gesellschaft für Drahtlose Telegraphie m. b. H., Berlin, Germany, a corporation of Germany

Application October 23, 1935, Serial No. 46,381
In Germany September 26, 1934

1 Claim. (Cl. 250—33)

In vertical antennas it is known, in order to shorten the length of the antenna and to obtain a more favorable current distribution, to provide at the upper end of the antenna a self-inductance, 5 capacity, or both. Such an arrangement is described in German Patent No. 205,494. In the known construction the self-inductance is previously adjusted once and for all to the desired wave range. The tuning is then controlled by 10 means of a variable tuning element disposed near the base of the antenna.

In accordance with the present invention, this antenna arrangement can be improved by making the self-inductance carried by the antenna variable for the purpose of tuning. The variation of 15 the reactance of this self-inductance is suitably accomplished by means of transmission and operation of a suitable handle provided in the proximity of the base of the antenna. The antenna proper is preferably formed of rods or tubes 20 placed on top of each other, whereby the length of the antenna may be varied by adding or removing single parts thereof. With this arrangement it is possible to vary the range of the antenna 25 radiation approximately proportional to the length of the antenna.

An embodiment in accordance with the invention is shown in the accompanying drawing, given by way of example, wherein the actual linear radiator is composed of rods or tubes 1, 2 30 and 3. A self-inductance 4 is fixedly secured to the upper end of the antenna, and to it a capacitive surface 5. For the control of the inductance there is provided a contact 6. This contact is 35 suitably controlled in such manner that it is fixedly secured to a control cord 7 and moved therewith. The cord is guided at the top of the antenna across a guide roller 8 fixedly mounted thereat, and at the bottom it is passed over a drive

roller 9 with adjustable mounting. The shaft of roller 9 has a suitable handle mounted thereon which, when turned, displaces the sliding contact 6.

In shortening the length of the radiator by decreasing the number of its individual parts, it will of course be necessary to also shorten the length of the cord accordingly. To this end a suitable winding up means 10 is provided which collects the superfluous length of the cord. In order to 5 tension the cord, the roller 9 will be moved downwards along a guide until the cord is sufficiently tensioned, and following this the bearing of this roller is fixedly secured in place.

The electrical connection with the transmitter 15 12 is obtained by means of a lead 13. The antenna is supported from an insulator 14 which may further be mounted to the transmitter casing. The insulator may also be provided with the attachment 11 serving for fastening the 20 roller 9.

What is claimed is:

An antenna comprising a vertical aerial composed of a plurality of serially arranged collapsible rods, an inductance coil connected to the top portion of the uppermost rod of said aerial, a capacity surface connected to the top of said coil, a metallic arm connected to one end of and arranged parallel to the length of said inductance coil, and means for tuning said antenna comprising a guide roller mounted near the top of said vertical aerial, a drive roller mounted near the base of said vertical aerial, and a cable passing over both said rollers, said cable having attached thereto a sliding contact arrangement engaging 30 both said coil and said arm for varying the self-inductance of said coil. 35

WILLI VOIGT.
